UNITED STATES PATENT OFFICE.

JOHN A. FRISCHKNECHT, OF CONNELL, WASHINGTON.

SNAP HOOK.

Application filed July 7, 1925. Serial No. 42,065.

To all whom it may concern:

Be it known that I, JOHN A. FRISCHKNECHT, a citizen of the United States, residing at Connell, in the county of Franklin and State of Washington, have invented certain new and useful Improvements in Snap Hooks, of which the following is a specification.

My invention relates to improvements in snap hooks and more particularly to locking means for the same.

It is an object of the invention to provide a hook having a spring pressed plunger for closing the hook opening and means for locking the plunger against movement to prevent accidental opening of the hook.

A further object of the invention is to provide a device of the above-mentioned character which is simple and durable in construction, reliable and efficient in operation and inexpensive to manufacture.

Other objects and advantages of the invention will be apparent during the course of the following description.

25 In the accompanying drawing forming a part of this specification and in which like numerals are employed to designate like parts throughout the same.

Fig. 1 is a side elevation of my improved snap hook,

Fig. 2 is a longitudinal sectional view of the same, and,

Fig. 3 is a perspective view of the locking lever.

35 In the drawing, wherein for the purpose of illustration I have shown a preferred embodiment of my invention, the hollow body or shank 5 is closed at both ends, having an integral loop 6 at one end and an integral hook 7 at the opposite end. A spring pressed plunger 8, slidably mounted in the body, is adapted to extend through an opening 9 in the end nearest the hook and engage the free end thereof, to close the gap 45 between the hook and body. A coil spring

10 having one end bearing against the end of the body and its opposite end against the end of the plunger, normally retains the latter in a locked position. The spring is 50 held in place by the opposed pins 11 which project from the end of the plunger and the end of the body, entering the convolutions of the spring. A knob 12 is formed integral with the pin 13 projecting from the 55 plunger, and movable in the slot 14 through

the body, whereby the plunger may be retracted to open the hook.

To prevent accidental opening of the hook a locking means is provided consisting of a lever 15 journaled on the transverse pivot 60 16 mounted in the sides of the casing 17, cast integral with the outside of the body. The forward end of the lever is forked, at as 18, being curved downwardly and extending through an opening 19 in the body. 65 The forked end engages an annular groove 20, formed adjacent the rear end of the plunger 8 holding the plunger against retraction until released. The opposite end of the lever 15 is bifurcated, as at 21, to receive the lower end of the push button 22 which is connected therewith by the pivot pin 23. The upper end of the push button extends through an opening 24, projecting 70 above the top of the casing. A spring 25 is mounted between the body and rear end of the lever normally holding the latter in a 75 locked position.

In use, the gap between the hook and shank is normally closed by the spring 80 85 pressed plunger having means for manually retracting the plunger to open the hook. To prevent accidental opening of the hook the forked end of the locking lever engages the annular groove in the plunger holding the same against movement. To release the lever, the push button connected therewith is depressed, lifting the forked end out of the groove and thereby, permitting the plunger 90 to be retracted to open the hook.

It is to be understood that the form of my invention herewith shown and described is to be taken as a preferred example of the same and that certain changes in the shape, size and arrangement of parts may be resorted to without departing from the spirit of the invention or the scope of the subjoined claims:

Having thus described my invention I claim:

1. In a snap hook, the combination of a hollow body having a hook formed at one end, a spring pressed plunger slidably mounted in said body adapted to abut the free end of said hook, an annular groove formed adjacent the rear end of said plunger and a forked lever pivotally mounted in said body adapted to releasably engage the groove in said plunger.

2. In a snap hook, the combination of a

hollow body having a hook formed at one end, a spring pressed plunger slidably mounted in said body adapted to abut the free end of said hook, an annular groove formed adjacent the rear end of said plunger, a casing formed integral with the outside of said body and having communication therewith, a lever pivoted in said casing having a forked end adapted to releasably engage the groove in said plunger, and means for releasing said lever.

3. In a snap hook, the combination of a hollow body having a hook formed at one end, a spring pressed plunger slidably mounted in said body adapted to abut the free end of said hook, an annular groove formed adjacent the rear end of said plunger, a casing formed integral with the outside of said body and having communication therewith, a lever pivoted in said casing having a forked end adapted to releasably engage said groove, spring means for normally holding said lever in engagement with said plunger and means connected with the rear end of said lever, extending through said casing for releasing said lever.

said groove and means for releasing said lever.

4. In a snap hook, the combination of a hollow body having a hook formed at one end, a spring pressed plunger slidably mounted in said body adapted to project through one end of the body and normally abut the free end of said hook, a casing formed integral with the outside of said body having communication with the interior thereof, a locking lever pivotally mounted in said casing having its forward end curved downwardly into the body, said forward end being forked and adapted to engage the groove surrounding the rear end of said plunger, springs means for normally holding said lever in engagement with said plunger and means connected with the rear end of said lever, extending through said casing for releasing said lever.

25 30 35 40
In testimony whereof I affix my signature.

JOHN A. FRISCHKNECHT.
